(57) **CLAIM**

The ornamental design for a wireless video transmitter, as shown and described.

DESCRIPTION

FIG. 1 is a front perspective view of a wireless video transmitter, showing my design.

FIG. 2 is a rear perspective view thereof.

FIG. 3 is a bottom perspective view thereof.

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof.

FIG. 9 is a bottom plan view thereof.

FIG. 10 is a partial enlarged view of the wireless video transmitter with a label number “10” in the FIG. 1; and, FIG. 11 is a partial enlarged view of the wireless video transmitter with a label number “11” in the FIG. 4.

The even dash broken lines illustrate portions of the wireless video transmitter that form no part of the claimed design. The dash-dot lines showing enlarged detail views in FIGS. 1, 4, 10, and 11 are for annotative purposes only and form no part thereof.

1 Claim, 11 Drawing Sheets
